(57) **CLAIM**

The ornamental design for an interactive touch screen display for room management, as shown and described.

DESCRIPTION

FIG. 1 is a front view of an interactive touch screen display for room management, showing the new design;

FIG. 2 is a front, lower perspective view thereof;

FIG. 3 is a rear, lower perspective view thereof;

FIG. 4 is a first side view thereof;

FIG. 5 is a rear view thereof;

FIG. 6 is a second side view thereof; and,

FIG. 7 is a rear, upper perspective view thereof.

Portions of the design shown in broken lines form no part of the claimed design.

1 Claim, 7 Drawing Sheets
